UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

PULL-CHAIN SWITCH

1,249,117.

Specification of Letters Patent.

Patented Dec. 4, 1917.

Application filed September 16, 1911. Serial No. 649,754.

To all whom it may concern:

Be it known that I, CHARLES J. KLEIN, a citizen of the United States, residing at Milwaukee, in the county of Milwaukee and State of Wisconsin, have invented new and useful Improvements in Pull-Chain Switches, of which the following is a full, clear, concise, and exact description, reference being had to the accompanying drawings, forming a part of this specification.

My invention relates to electric snap switches of the pull chain type. The broad features of the present invention are covered in my co-pending application, Serial No. 648,035, filed Sept. 7, 1911.

One of the objects of the present invention is to provide a simple, compact switch mechanism which may be economically manufactured. Another object is to provide a switch mechanism having a quick break or quick make and break action. Another object is to provide a switch mechanism having certain features by which it is particularly adapted to be operated by a pull cord or chain. Another object is to provide means whereby the effective pull applied to the switch mechanism is much greater than the force applied to the pull chain. Another object is to provide a switch mechanism having an adjustable tension device whereby the weight of the depending cord or chain may be compensated for. A further object is to provide a pull chain switch device adapted particularly for use in connection with lamp sockets, one of the features being the provision of an insulating supporting base for the switch, having an opening therethrough for the chain or cord. Other objects will be apparent from the more detailed description which follows:

The invention may be embodied in various forms. In the accompanying drawings I have illustrated several embodiments of the invention which I have worked out in practice and which have certain commercial advantages. The invention is not limited to these forms, however. By virtue of certain features which are found in all of the switch mechanisms illustrated, said mechanisms are adapted primarily to be operated by a pull cord or chain. Said switch mechanisms, however, may of course be operated by a push button, lever, rotatable key, or other suitable means if desired.

The various forms of the invention illustrated all include the same broad features or elements set forth in my co-pending application referred to above. These main elements are the following. A rotatable bridging member adapted to open and close a circuit across suitable terminals; a rotatable actuating member therefor; an operating member adapted to coöperate with the faces of said actuating member in such a manner that when the actuating member and the operating member are moved relatively to each other, an accelerated step by step rotation is imparted to said actuating member.

In the drawings:

Figure 1 is an elevation of a ceiling switch with the casing shown in section.

Fig. 2 is a sectional elevation on the line 2—2 of Fig. 1.

Fig. 3 is an elevation similar to Fig. 1 but with the parts moved to a point where the rotatable contact member is about to snap to off position.

Fig. 4 is a section on the line 4—4 of Fig. 2.

Fig. 5 is an elevation of another form of switch mechanism in which the actuating members are yielding but not resilient as in the first form described.

Fig. 6 is a further elevation thereof showing the parts moved to a position they occupy temporarily during the ordinary sequence of operation.

Fig. 7 is a sectional elevation on the line 7—7 of Fig. 5.

Fig. 8 is a sectional elevation of a pull cord lamp socket switch with the casing shown in dotted outline.

Fig. 9 is a sectional elevation taken at right angles to Fig. 8.

Fig. 10 is a view of the parts in the upper half of the insulating casing, as indicated by the line 10—10 in Fig. 8.

Fig. 11 is a view similar to Fig. 10, but with the movable switch parts moved through a partial cycle of operation.

Fig. 12 is a view of the lower half of the insulating casing as seen from above.

Referring to Fig. 1, the switch elements are mounted on a suitable base or support 1 of insulating material, which may be of any suitable configuration, and is illustrated as adapted to be secured to a ceiling or other horizontal support. The ~~base~~ supports the

relatively fixed contact members 2 to which the leads are secured in any suitable manner. Each contact member 2 is preferably bifurcated whereby two resilient tongues or strips 3 and 4 are provided. The resilient strips 3 are adapted to be bridged by the rotatable circuit-closing or bridging member 5. The resilient strips 4 constitute the operating members, one of which is provided with a shoulder or catch 6, preferably struck up therefrom. This resilient member is the main operating member, the other resilient strip 4 being supplemental and desirable, though not essential. The rotation of the bridging member 5 is effected by the actuating member 7 which consists preferably of a block of polygonal outline. In the present instance it is square, although the number of faces may be varied. Said block 7 and bridging member 5 rotate together and are mounted on a screw 8 carried by a reciprocating plate 9. The bridging member 5 may preferably be insulated from the metallic plate 9 and from the parts associated therewith, but this is not essential, as long as it is insulated from the stationary contact members when in open position. A metallic cover plate 10 is suitably secured to the insulating base and supports and guides the movable parts heretofore described. This plate is provided with a slot 11 through which extends a screw 8. The plate 9 is adapted to slide up and down in the free space between the cover plate 10 and the adjacent insulating base 1, a suitable recess or slot having been provided for this purpose. The bridging member 5 and the actuating block 7 are accordingly reciprocated on the opposite side of the cover plate 10.

The sliding plate 9 and consequently the parts carried thereby, are normally maintained in uppermost position as shown in Fig. 1, by means of the spring 12 suitably mounted and having one end hooked under a projection or catch 13 on said sliding plate. In order to lower said sliding plate and the parts carried thereby, the pull chain 14, or suitable equivalent flexible means is provided. The chain has one end caught in the fork 15, preferably cut out of the cover plate 10, and is looped around the pulley 16, rotatably mounted on the screw 8. When the chain is pulled by hand, it is apparent that the pulley 16, the shaft or screw 8 on which it is mounted, and all the parts carried by said screw, will descend. When the chain is released, the spring 12 will restore the parts to upper position. The chain being looped once over the pulley, the downward movement of said pulley will be one-half the downward movement of the free end of the chain, hence the downward force applied against the tension of the spring 12 will be double the downward pull applied to the free end of the chain. There are two

important advantages in this arrangement. One is that a comparatively light pull will operate the switch mechanism against the action of the relatively strong spring 12 which may be employed where the pull chain is long and rather heavy and where consequently the weight of the chain has to be supported by said spring. The second advantage is that in a compact switch mechanism such as this, where the actual movement required is not great, it is advantageous to permit the end of the chain to move farther than the required distance in response to a careless jerk or pull of unnecessary violence by careless operators, accustomed perhaps to a longer pull.

As the actuating block 7 slides downwardly between the parallel strips 4 which press against the same, the lower corner of said block is caught by the shoulder 6 and thereby retarded, as seen in Fig. 6, the continued downward movement of said block causing it to snap around a quarter of a revolution. In the position shown in Fig. 3 the block is about on the dead center and the contact strips 3 are still bridged by the bridging member 5, whereby the circuit remains closed. As the block rotates beyond the dead center, the resilient actuating strips 4 snap toward each other and throw the block ahead thereby opening the circuit with a quick snap action. As soon as the chain is released, the parts are restored to normal upper position except that the circuit is now open instead of closed. The next downward pull of the chain causes the bridging member to snap to closed position, the same cycle of operation being performed as in the case first described.

As the actuating members 4 have no electrical function, they may, of course, be entirely independent of contact members 2 and 3. They are formed integrally therewith simply for economy of manufacture. Furthermore, only one of these two operating members is essential, namely, the one with the shoulder. The advantage of having two, however, is that the side thrust applied to the actuating block is substantially balanced, whereby binding of the sliding parts is eliminated.

Although in the construction illustrated the actuating block moves and the operating member or members is stationary, it is apparent that the relative arrangement may be reversed and that said operating member may slide along the block which may be fixed or both elements may slide, as long as the proper relative movement is obtained. Furthermore, it is apparent that the switch elements described may be actuated in various ways other than by a pull cord, for example by a push button, lever or rotatable key, and that they may be mounted differently to adapt them for different specific

uses. In the construction illustrated, the switch being adapted more particularly for a ceiling switch, the parts are inclosed in a protecting or ornamental casing 17, secured by suitable insulating bushings and nuts 18 and 19, and which are supported by a bracket 20 in such a manner that the casing may be readily removed for inspection whenever desired, by simply unscrewing the lower nut.

In the form of switch mechanism illustrated in Figs. 5, 6 and 7, the rotation of the actuating block and bridging member is accomplished by substantially the same means described above. The operating members 21, however, although yielding, are not resilient. They are preferably pivoted at a common point 22 and impelled toward each other by a spring 23. As the actuating block moves up and down, one corner is caught by the projection 24, the pivoted members 21 being spread apart and snapping together again to impart a quick throw to the bridging contact. The detailed operation of the device will be apparent from the drawings, some of the reference characters being the same as those applied to the first form of switch described, where the parts are substantially identical and perform the same functions. It is to be noted that in this construction the spring 23 performs the double function of returning the parts to their initial position and maintaining the operating members 21 in engagement with the actuating block.

In Figs. 8, 9, 10 and 11, I have illustrated a lamp socket switch adapted to be operated by a pull cord or chain.

The switch elements are supported by an inclosing insulating block or member made in two separable parts 25 and 26. Each part is provided with a reduced neck or extension, the two extensions when combined forming an insulating bushing 27 which projects through a suitable opening in the metallic casing 28 which, together with the cap 29, ordinarily incloses lamp sockets of standard size. The bushing may be omitted however.

The usual screw-threaded shell 30 and center contact 31 are mounted on the insulating base to furnish the usual lamp contacts. The conductors or terminals are brought down through any suitable slot, opening or groove in the insulating body 25 and are secured to the terminal screws 32 and 33, the terminal screw 32 being carried by the lower, and the terminal screw 33 being carried by the upper half of the insulating base. The circuit extends from the terminal screw 32, through the strip 34 to the threaded shell 30, held in place by the curved strip of metal 35, secured by suitable screws 36 in addition to the strip 34. The circuit is traced from the incandescent lamp,

through the center contact member 31 and thence through the switch mechanism to the terminal screw 33.

The switch mechanism in its main elements is similar to that described in connection with the first form illustrated and the same reference characters have been used for both forms where the parts are substantially the same and have the same functions.

From the preceding description it will be apparent that when the chain 14 is pulled and released, the contact bridging member 5 will be snapped around to successively open and close the circuit in the manner previously described. The chain 14 is guided in its movements by the insulating bushing 27 which, being formed integrally with the insulating supports 25 and 26, is perfectly rigid therewith and exerts no direct pressure on the external casing 28 such as would tend to cause a looseness or play between these members. Furthermore, this bushing being split or made in two separable halves, provides a ready means for arranging the chain 14 properly therein.

The spring 12 which holds the movable parts of the switch normally in extreme position, is coiled about a projecting pin 37 carried by the sliding plate 9. The opposite ends of said spring are relatively fixed, one end being adapted to be dropped into any one of a number of notches provided in a suitable plate or support 38, for the purpose of adjusting the tension of the spring. As seen particularly in Figs. 10 and 11, this plate is arranged near the periphery of the insulating block 25, so that the free end of the spring may be readily grasped by the hand when the inclosing casing is removed for the purpose of adjusting the spring tension. One advantage of having the spring readily adjustable is that the weight of the depending chain 14 may be compensated for by putting the spring under additional tension. The arrangement by which the power applied to the free end of the chain is doubled where applied to the switch mechanism, is the same as in the form previously described.

The switch mechanism as a whole is secured to the upper insulating block 25 and is therefore removable with said block when the same is separated from the lower block 26. The main supporting plate 39 for the movable parts of the switch is preferably secured to the insulating block 25 by lugs 40, which pass through suitable apertures in said block and have their ends bent over to grip said block. The plate 39 is provided also with additional lugs 41 struck up therefrom, which position said plate from the insulating block 25 and act as guides for the reciprocating plate 9.

From the above description it will be ap-

parent that the invention is not limited to the particular forms illustrated, nor to the details thereof. I desire, therefore, that all the above statements shall be interpreted merely as descriptive and not in a limiting sense. The invention is intended to cover other suitable equivalent means for accomplishing the desired results and falling within the scope of the appended claims.

10. What I claim as new and desire to secure by Letters Patent of the United States is:

1. In an electric switch, in combination, a contact actuating member rectilinearly movable and rotatable in a single plane, a pull cord fixed at one end and having a reflexed portion to act upon said member for moving the same rectilinearly, and means for effecting accelerated rotation of said member when moved rectilinearly but independently of 20 the rate of said rectilinear movement.

2. In an electric switch, in combination, a contact actuating member movable bodily and rotatably in a single plane, a pull cord looped about said member to move the same 25 bodily at a reduced speed and means for effecting an automatic snap rotation of said member when moved bodily at any speed.

3. In an electric switch, in combination, a rotatable and bodily movable actuating member, a yielding catch for turning said member as it moves, a fixed securing member and a pull cord adjustably anchored at one end within said latter member and having a reflexed portion to act upon said 35 actuating member for moving the same rectilinearly.

4. In an electric switch, a rotatable and bodily movable actuating member, and a pull cord having a reflexed portion for co- 40 operation with said member whereby the bodily movement of said member is caused to be relatively less than the movement of said cord.

5. In an electric switch, in combination, a 45 rotatable and bodily movable actuating member, a yielding member having a shoulder for turning said actuating member as it moves, a relatively fixed catch and a pull cord adapted to have different portions there- 60 of anchored therewith for determining the effective length of said cord and having a reflexed portion to act upon said actuating member for moving the same at a relatively reduced speed.

6. In an electric switch, substantially parallel stationary contacts, a rotatable bridging member therefor, a sliding support for said bridging member, an actuating block and a pulley also carried by said support, 60 a chain looped over said pulley having one end held and the other end free, whereby said support and associated parts may be

moved by said chain, and yieldable means for engaging said block during its movement to release it with a snap movement. 65

7. In an electric switch, a supporting plate having guiding lugs thereon, a sliding plate guided by said lugs, a post carried by said sliding plate, a rotatable contact member, actuating block and pulley mounted on said 70 post, a spring tending to hold said sliding plate and the parts carried thereby in normal position, a pull chain looped over said pulley and having one end secured to said supporting plate and the other end free to 75 be pulled to move said sliding plate and associated parts from normal position against the action of said spring, stationary contacts adapted to be bridged by said rotatable contact member to close a circuit, and a 80 yielding obstruction adapted to engage a corner of said block during said movement, whereby said block and said rotatable contact member may be snapped to successively angular positions. 85

8. In an electric switch, in combination, a bodily movable operated member, a pull cord operating member therefor and an operative connection between said members whereby a given movement of the latter 90 imparts a lesser movement to the former.

9. In an electric switch, in combination, a movable member, a pull cord for moving said member from normal position, a coil spring for retracting said member to normal position, and a fixed member having a plurality of recesses in any one of which an end of said spring may be anchored for varying the tension thereof. 95

10. In a lamp socket switch, in combination, 100 an insulating support for the switch mechanism, a casing for said support, a bushing projecting through an opening in said casing, said bushing being integral with said insulating support and adapted to guide 105 a pull cord for the switch mechanism.

11. In a lamp socket switch, an insulating base having a recess in the side thereof, a spring suitably mounted to maintain the movable switch elements in normal position, 110 a plate having notches therein mounted in said recess, said spring being adjustable by moving one end thereof into the various notches, said end projecting near the side of said insulating base, whereby said spring 115 may be readily adjusted.

In witness whereof, I have hereunto subscribed my name in the presence of two witnesses.

CHARLES J. KLEIN.
